COFFEE TABLE

Kenneth R. Culliss, 9737 Larsen St.,
Shawnee Mission, Kans. 66214

Filed Mar. 27, 1969, Ser. No. 16,475

Term of patent 14 years

Int. Cl. D6—01

U.S. Cl. D33—14

Fig. 1.

Fig. 2.

*Fig. 3.**Fig. 4.*FIG. 1 is a perspective view of a coffee table embodying my design.

FIG. 2 is a side elevational view thereof.

FIG. 3 is an end elevational view thereof.

FIG. 4 is a top plan view thereof.

The table is characterized by the shape of the top in combination with the specifically configured leg supports as well as the angled relationship between said paired leg units, as best illustrated in FIG. 4.

I claim:

The ornamental design for a coffee table, as shown and described.
